US0D1042618S

(12) **United States Design Patent** (10) Patent No.: **US D1,042,618 S**
(45) Date of Patent: ** Sep. 17, 2024

(54) **MULTIFUNCTION PRINTER**

(71) Applicant: **Zhuhai Pantum Electronics Co., Ltd.**,
Guangdong (CN)

(72) Inventors: **Aiguo Yin**, Zhuhai (CN); **Jibing Peng**,
Zhuhai (CN); **Geng Wang**, Zhuhai (CN);
Ke Mou, Zhuhai (CN);
Weisheng He, Zhuhai (CN); **Huizhao Deng**,
Zhuhai (CN); **Tian Wang**, Zhuhai (CN);
Rubo Li, Zhuhai (CN);
Dongrong Liu, Zhuhai (CN)

(73) Assignee: **Zhuhai Pantum Electronics Co., Ltd.**,
Zhuhai (CN)

(**) Term: **15 Years**

(21) Appl. No.: **35/517,530**

(22) Filed: **Apr. 27, 2023**

(80) **Hague Agreement Data**

Int. Filing Date: **Apr. 27, 2023**

Int. Reg. No.: **DM/229429**

Int. Reg. Date: **Apr. 27, 2023**

Int. Reg. Pub. Date: **Jun. 16, 2023**

(30) **Foreign Application Priority Data**

Dec. 21, 2022 (CN) 202230851479.5

(51) LOC (14) Cl. **14-02**
